SKIING EXERCISE DEVICE OR THE LIKE

Chester T. Schandlmeier, 1027 S. 23rd Ave.,
Bellwood, Ill.

Filed May 26, 1961, Ser. No. 65,358

Term of patent 14 years

(Cl. D34—14)

Fig. 1.

Fig. 2.

FIG. 1 is a top perspective view of the skiing exercise device or the like of the present invention;

FIG. 2 is a top plan view of the device shown in FIG. 1;

FIG. 3 is a bottom view of the device shown in FIG. 1;

FIG. 4 is a side elevational view, taken along the right side of FIG. 2; and

FIG. 5 is an end elevational view, taken along the upper edge of FIG. 3.

The elevational view taken along the left side of FIG. 2 is the mirror image of FIG. 4.

I claim:

The ornamental design for a skiing exercise device or the like, substantially as shown and described.
